Attorneys

UNITED STATES PATENT OFFICE.

EARCLE DICKSON, OF KITTANNING, PENNSYLVANIA.

CHEST.

Application filed January 5, 1925. Serial No. 642.

To all whom it may concern:

Be it known that I, EARCLE DICKSON, a citizen of the United States, residing at Kittanning, in the county of Armstrong and

5 State of Pennsylvania, have invented certain new and useful Improvements in a Chest, of which the following is a specification:

This invention relates to improvements in 10 chests or like receptacles, which may be constructed of relatively light materials, and embodies an improved bracing and locking construction to make the same strong and durable.

15 The primary object of this invention is the provision of an improved chest, particularly well adapted for receiving tools or the like, and which embodies walls and a closure preferably constructed of some light material such as wood, and embodying a novel 20 bracing and reinforcing construction rendering the same particularly well adapted to withstand rough usage.

25 A further object of this invention is the provision of a chest, box, trunk, or like receptacle embodying a novel bracing and reinforcing construction, and having a novel locking arrangement cooperating therewith in an efficient and compact working relation.

30 Other objects and advantages of this invention will be apparent during the course of the following detailed description.

35 In the accompanying drawings, forming a part of this specification, and wherein similar reference characters designate corresponding parts throughout the several views,

Figure 1 is a perspective view of the improved chest or receptacle, showing the same closed and locked.

40 Figure 2 is a transverse section taken through the improved chest in its closed locked position.

45 Figure 3 is a skeleton view of the bracing, reinforcing, and locking details of this invention.

50 Figure 4 is a fragmentary sectional view taken substantially on the line 4-4 of Figure 5, and more particularly showing the improved locking features of the invention.

55 Figure 5 is a fragmentary view, partly in section, showing locking details of the invention.

60 Figure 6 is a fragmentary perspective view of the body and lid or closure of the chest, adjacent a locking device, with the lid

slightly lifted to more clearly designate the cooperating locking details of the improved chest.

In the drawings, wherein for the purpose of illustration is only shown a preferred embodiment of this invention, the letter A may generally designate the improved chest, which may consist of the body or receptacle portion B having a lid or closure C hingedly cooperating therewith, and embodying improved reinforcing and locking details D.

The improved body portion B may include a bottom 10; front and rear walls 11 and 12 respectively; and end walls 13 and 14. These walls and the bottom are constructed of some light weight material, preferably wood, the same being of approximately $\frac{7}{8}$ " in thickness for the conventional type of chest, although the thickness and the dimensions of these walls and the bottom may be varied to suit. The body B is of course formed to provide the article receiving compartment 15, and is open at the top thereof and over which top the closure C cooperates.

The closure C includes the top wall 16, front flange 17; rear flange 18; and end flanges 19; these flanges being relatively short, and together with the top wall 16 being formed of light weight material, such as wood, and preferably of the same nature as the material of which the body walls are formed. The pocket provided inwardly of the closure C forms an extension of the compartment 15 when the closure is shut, as can be seen from Figure 2 of the drawings.

The closure C is hingedly connected to the body B by means of hinges 21 and 22. Each of these hinges includes a section 24 bolted or secured, as by carriage bolts 25^a, to the rear wall 12 at the top thereof, and being countersunk inwardly of the outer surface thereof. Each of these hinges furthermore includes a section 25 hingedly connected to the section 24, and being secured to the rear flange 18 of the closure C by means of carriage bolts 26 or the like and substantially as is illustrated in Figures 2 and 3 of the drawings. These sections 25 are also countersunk inwardly of the outer surface of the rear flange 18 of the closure C, in order to compactly receive reinforcing details of the invention, as will be subsequently described.

Referring to the reinforcing and locking construction D, the same has been provided in order to render the chest body and clo-

sure strong enough to withstand the hardest usage, with the reinforcement still compactly arranged. The locking details which are cooperatively related with the reinforcing structure have been provided to render the chest burglar-proof to the highest degree possible with a light weight chest.

Referring to the body reinforcing details, metal corner clips 28, 29, 30 and 31 are secured at the lower corners of the body B; said clips being of triangular pocket formation, and each including a plate portion adapted to overlie a front or back wall, a plate portion adapted to overlie an end wall, and a bottom plate portion adapted to overlie the bottom wall. Diagonal brace straps 32 and 33 are provided for the bottom wall 10 of the body B; the same being disposed at the inner surface of the bottom wall 10, and having the ends thereof secured to the bottom plate portions of the triangular corner clips 28 to 31 inclusive, as by means of carriage bolts or securing elements 34. It is preferred that the diagonal straps 32 be countersunk inwardly of the inside surface of the bottom 10, so that the top surface of this strap 32 lies flush with the surface of the bottom 10, as is illustrated in Figure 2 of the drawings. The diagonal strap 33 on the other hand lies on the top surface of the bottom 10 and at the point of crossing of the same with the diagonal strap 32 a carriage bolt or securing element 35 is provided, which extends through the bottom wall 10, as do also the securing elements 34, so that the diagonal braces for the bottom wall are secured to the corner clips and to the bottom wall also.

At the ends of the body B, just below the top edges thereof, and at the outer surface of said end walls 13 and 14, reinforcing and connecting straps 37 and 38 are respectively provided for the walls 13 and 14, having right angled end portions 39 bent to overlie the front and rear walls 11 and 12 of the body B. The end wall 13 of the body B is provided with diagonal cross braces 40 and 41, arranged at the inside surface of the end wall 13; the brace 41 preferably being countersunk inwardly of the inside surface of said wall. The ends of these diagonal braces 40 and 41 are secured to the corner clips 28 and 29 as by carriage bolts or like securing elements 42. In analogous manner the upper ends of the cross braces 40 and 41 are secured as by carriage bolts or securing elements 43 to the top strap or brace 37. At the point of intersection of the diagonal braces 40 and 41 a carriage bolt or like securing element 44 fastens said diagonal braces to each other and to the end wall 13, and the bolts or securing elements 42 and 43 are secured to the end wall 13.

Diagonal braces 45 and 46 are provided at the inside surface of the end wall 14; the

brace 45 being countersunk inwardly of the inner surface of said end wall, and the lower ends of said diagonal braces being riveted or bolted as by carriage bolts or analogous securing elements 47 to the corner clips 30 and 31 respectively. At their upper ends these diagonal braces or straps are riveted or bolted as by carriage bolt elements 48 to the top brace bar 38, and at the point of crossing of the diagonal braces 45 and 46 a wall securing bolt 49 is provided; all of the rivets or bolts 47, 48, and 49 extending through the end wall 14.

Diagonally disposed and crossing braces 50 and 51 are provided at the inside surface of the back wall 12; it being preferred to countersink the brace or diagonal strap 50 inwardly of the inside surface similar to that illustrated in Figure 2 of the drawings. At their upper ends the diagonal braces 50 and 51 are respectively secured to the in-turned portions 39 of the top braces 37 and 38 as by means of analogous securing elements 52 and 53, which are likewise secured through the rear wall 12. At their lower ends the said diagonal bars or braces 50 and 51 are secured by similar bolts to the corner clips 31 and 28 respectively. At the intersection of the diagonal braces 50 and 51 a connecting bolt 54 is provided which secures the diagonal braces 50 and 51 and to the wall 12.

At the inside surface of the front wall 11, diagonal reinforcing bars 55 and 56 are provided; the entire diagonal member 55 being countersunk inwardly of the inner surface of the front wall 11, so that the outer surface lies flush with the inside surface of the said wall 11, and in similar manner the upper portion of the other diagonal brace 56 is bent at 57, just above the point of intersection of the diagonals 55 and 56, so that said upper portion of the diagonal 56 is likewise countersunk in the inner surface of the wall 11. The lower ends of the diagonal members 55 and 56 are respectively secured as by bolts 58 to the corner clips 29 and 30 respectively, which also secures said diagonals through the front wall 11. At their upper ends the diagonals 55 and 56 are respectively bolted to the inwardly flanged ends 39 of the top braces 38 and 37 respectively, as by bolts 59 which are secured through the front wall 11. At the point of intersection of the diagonal members 55 and 56 a wall connecting bolt 60 is provided, and at opposite sides of this intersecting point of the diagonals, other wall securing bolts 61 may be provided, as is illustrated in Figures 1 and 3 of the drawings.

Transverse reinforcing hoops 62 and 63 are provided for the body B, preferably two of the same being provided, and the same being located about one fourth inwardly from the end walls of the body B. Each of

the hoops 62 and 63 includes connecting portions extending about the front and rear walls and along the bottom of the body B. At their upper ends at the back wall 12, the 5 hoops 62 and 63 are riveted or bolted, by bolts 25^a to the hinged section 24 of the hinges 21 and 22; said bolts 25^a preferably extending through the rear wall 12, as above mentioned. At their upper ends at the front 10 wall of the body B, each of the said hoops are inwardly flanged at 65, in spaced relation over the bottom surface of a recess 67 provided inwardly of the normal top edge 68 of the front wall 11; the securing hoops 15 62 and 63 furthermore including depending end portions 69 at the inside surface of the front wall 11, which adjacent their free ends are bolted as at 70 to the diagonal braces 55 and 56; the wall 11; and the outer portions 20 of the hoops 62 and 63, as is clearly shown in the drawings. It is thus seen that at their upper ends the hoops 62 and 63 each provides a lock receiving opening 72, in the recess 67, adapted to cooperate in receiving 25 certain locking mechanism to be subsequently described.

Substantially U-shaped end bracing hoops 75 and 76 are provided at the end walls 13 and 14, each of these hoops including an end 30 wall engaging portion 77 bolted as by bolts 78 to the end wall diagonal braces. Furthermore, each of these end hoops 75 and 76 includes the countersunk front wall and rear wall abutting portions 79 which at their 35 outer ends are secured as by bolts 80 to the hoops 62 and 63, as well as to the front and rear walls and the diagonal braces for said front and rear walls, and as is clearly illustrated in Figures 1 and 3 of the drawings. 40 It is also to be noted that the hoops 62 and 63 at their bottom portions may be secured as by bolts 81 to the bottom 10 of the body B, and to the diagonal braces for said bottom 10, as is illustrated in Figure 3 45 of the drawings.

Referring to the reinforcing and locking features of the closure C, triangular shaped angle clips 82, 83, 84 and 85 are provided at the corners of the closure, including 50 plates which overlie the outer surfaces of the top 16 and front, back, and end wall flanges thereof. Diagonal braces 86 and 87 are provided for the top 16, positioned at the inside surface; it being preferred to 55 countersink the brace 86. The brace 86 at its ends is secured as by bolts 88 and 89 to the corner clips 83 and 84; these bolts extending through the top wall 16. In similar manner the ends of the diagonal brace 87 60 are secured by means of bolt 90 and 91 to the corner clips 83 and 85 respectively. These diagonal braces at their crossing point are secured together, and to the top 16 by means of a bolt 92.

65 A pair of spaced parallel substantially U-

shaped transverse braces 95 and 96 are provided for the closure C, at their rear ends being right angled at 97, and secured to the hinged portion 25 of the hinge 21, as by the bolts 26 above mentioned. These transverse 70 braces 95 and 96 at the front of the closure C, and at the outer surface of the front flange 17 are downturned in right angular relation, at 98; thence inwardly turned at 99 below the lower edge 100 of the closure 75 flange 17; thence upturned at 100 at the inside surface of the front flange 17; thence flanged at 101 into parallel abutting relation with the bottom surface of the top 16, and being secured to said top 16 by means of 80 bolts 102. The front ends of the transverse braces 95 and 96 are thus seen to loop about the flange 17, and they provide aligning openings 103 between the turned flanges 99 and the lower edge 100, which are adapted 85 to align with the opening 72 provided by the hoop 62, when the closure C is shut. In this relation of parts the upper end of the hoop 62 at the front wall of the chest is disposed in the space between the facing edges of the 90 transverse braces 95 and 96, so that a locking member 105 may be slipped through the openings 72 and 103, to lock the closure of the chest.

Transverse braces 106 and 107 altogether similar to the braces 95 and 96 are provided adapted to cooperate with the hoop 63, and at their rear ends being downwardly flanged at 108 and secured to the hinge 22, as by means of the bolts 26. At their forward ends they are downturned in right angular relation, at 109, exteriorly of the closure front flange 17; thence inwardly flanged at 110; thence upwardly flanged at 111 at the 105 inside of the front closure flange 17; thence at their ends bent to underlie the top 16 of the closure, at 112; the last flange 112 mentioned being secured as by bolts 113 to the top 16. The transverse braces 106 and 107 110 at their front ends provide transverse openings 103^a below the lower edge 100 of the closure flange 17, in manner similar to that illustrated and described for the transverse braces 95 and 96, and adapted to cooperate 115 with the upper end of the hoop 63, in receiving the locking member 115.

Referring more specifically to the locking feature of the closure C on the body B, the locking members 105 and 115 are mounted 120 respectively in recesses 116 and 117 provided inwardly of the top edge 68 of the front wall 11; and each of these locking members includes a body portion 118, and a locking shank 119, as is illustrated in Figure 6. The locking shanks slide toward each other in order to place them in their recesses to remove said locking shanks from connection with the aligning openings of the body hoops 62 and 63 and the transverse braces 95, 96, 106 and 107; and when they are lo- 130

cated in their recesses 116 and 117, out of locking relation, the deeper recesses 67 do not receive any part of the locking shanks 119, and said locking shanks when retracted 5 permit the closure C to be lifted on its hinge pintles as a pivot. Suitable key operated lock structures 125 may be provided for each of the locking members 105 and 115, the same being mounted in the wall 11, providing casings with key openings 126 therein, and with locking bolts 127 which operate upwardly through the recesses 117, in a direction at right angles to the sliding movement of the locking members 105 and 115, so that 10 said locking bolts 127 may enter transverse openings 129 in the locking members 105 and 115, when said locking members are in locking position, in order to prevent sliding of the locking members to an unlocked position. To facilitate the sliding of the locking members 105 and 115 suitable edge openings or passageways 130 may be provided therein, to receive the key of the locking structures 125 to facilitate sliding of said members to an unlocked position. It is to be 15 particularly noted that at the juncture of the locking shanks 119 with the body 118 of the locking members 105 and 115, suitable shoulders are provided which are adapted to 20 abut the end edges of the transverse closure braces to limit the locking movement of the members 105 and 115, and when in such position the lock structures 125 may be key operated so that the bolts 127 may enter or be 25 withdrawn with respect to the openings 129.

To properly reinforce the top edge of the front wall 11 and to seal the recesses 67 and 116 and 117 from communication with the chest compartment, it is preferred to provide a short piece of strap metal 135 secured at the inside surface of the front wall 11, and rearwardly of this is positioned a bracing member 136, which extends for the 30 length of the front wall 11, and is secured at its ends to the end braces 37 and 38, and also secured to the piece 135 as by bolts 140, which extend through the front wall 11.

From the foregoing description of this invention it is apparent that a novel type of 35 chest has been provided, which is light in weight, although which is properly reinforced and provided with locking mechanism to render the same burglar-proof. The bracing and locking features are of particular merit, and while it is preferred to provide a chest having approximately the dimensions of 10" x 30" x 13", yet these dimensions may be departed from if desired. The 40 diagonal cross bars of all of the walls and the closure have one of each of the same countersunk flush with the surface of the member in which it is disposed, and the front wall of the body B has also the upper portion of the other diagonal member 45 countersunk. Wherever the reinforcing

braces and straps cross each other, it is preferred to bolt the same together to each other and to the abutting wall.

Handles 150 are provided at the end walls 13 and 14, secured by bolts 151 to the said 50 walls and the inside diagonal braces.

Various changes in the shape, size, and arrangement of parts may be made to the form of invention herein shown and described, without departing from the spirit of this invention or the scope of the claims. 75

I claim:

1. A chest comprising a bottom, front and rear walls, end walls, a closure, hinges pivotally connecting the closure to the rear wall, 80 corner clips for said closure, corner clips for the lower corners of the chest, diagonal braces secured at the inside surfaces of the walls of the chest to said walls and at their lower ends to said corner clips of the chest, diagonal braces interiorly secured to the closure and to the closure corner clips, transverse bands enveloping the front, bottom and rear walls of said chest, transverse bands for said closure, and locking means 90 cooperating with said bands in securing the closure on said chest.

2. A chest of the class described comprising a body including a bottom, front and rear walls, end walls, lower corner clips for the body exteriorly thereof, diagonal cross braces at the inside surfaces of the front, rear and end walls secured at their lower ends to their respective walls and to said corner clips, diagonal cross braces for the 100 bottom of the body secured at their ends to said lower corner clips, cross straps at the upper edges of said walls of the body, means securing the upper ends of said diagonal cross braces of the walls of the body to said cross straps, closure means hingedly connected to said body at the rear wall, said closure means including a top, depending front and rear flanges and end flanges, corner clips exteriorly secured to said closure, diagonal cross braces at the inner surface of the top of said closure secured at their ends to said top and to the corner clips of the closure. 110

3. A chest of the class described comprising a body including a bottom, front and rear walls, end walls, lower corner clips for the body exteriorly thereof, diagonal cross braces at the inside surfaces of the front, rear and end walls secured at their lower ends to their respective walls and to said corner clips, diagonal cross braces for the bottom of the body secured at their ends to said lower corner clips, cross straps at the upper edges of said walls of the body, means securing the upper ends of said diagonal cross braces of the walls of the body to said cross straps, closure means hingedly connected to said body at the rear wall, said closure means including a top, depending front and rear flanges and end flanges, corner clips ex- 120 125 130

- teriorly secured to said closure, diagonal cross braces at the inner surface of the top of said closure secured at their ends to said top and to the corner clips of the closure, a plurality of transverse hoops for the body reinforcing the bottom front and rear walls, a plurality of transverse hoops for said closure reinforcing the front and rear flanges and the top thereof, and locking means cooperating with said hoops in maintaining the closure locked on said body.
4. A chest comprising a body portion including a bottom, front and rear walls, and end walls, a closure hingedly connected to said body at the rear wall, transverse reinforcing hoops for the body extending about the front bottom and rear walls and at their upper ends providing openings at the top edge of said front wall of the body, transverse hoops across the closure in cooperating position with the hoops of said body providing openings at the free edge of said closure adapted to align with the openings of said hoops of the body when the closure is in shut position, and locking means adapted for extension through said aligning openings to lock the closure on the body.
5. A chest of the class described comprising a body including front and rear walls, a bottom, and end walls, a closure, hinges connecting the closure to the rear wall of the body, transverse hoops connected about the body along the front and rear walls and bottom thereof and at the front wall along the upper edge thereof providing openings, said hoops at the rear wall being connected with said hinges, transverse hoops carried by the closure connected at their rear ends to said hinges and at their front ends along the front edge of said closure providing openings adapted to align with the openings of the hoops of said body when the closure is in shut position, and slideable locking members carried by said body adapted to extend through the aligning openings of the hoops of said body and closure when the latter is shut.
6. In a chest of the class described the combination of a body portion including a bottom, front and rear walls and end walls, a closure hingedly connected to the rear wall of said body, said front wall of the body at the upper edge thereof being provided with a recess, a locking member slideable in said recess longitudinally of the chest, and means carried by the front wall of the body and by said closure at its swinging end providing openings adapted to align when the closure is shut whereby the locking member may extend into said openings for securing the closure in locked relation on the body.
7. In a chest of the class described the combination of a body providing a bottom, front and rear walls, end walls, said front wall along the upper edge thereof being provided with a recess inwardly of said upper edge, a transverse hoop for the body including portions extending about the bottom and front and rear walls, means securing said hoops to said walls and bottom, said hoop at the front wall providing an upper end loop over the top edge of the recess of said front wall, a closure hingedly connected to said body at the rear wall, a pair of spaced members extending transversely of the closure and at the free end thereof extending outwardly of the edge of said closure and providing aligning openings at said edge, said closure when shut adapted to have the ends of said pair of members extend into the recess at the top of the front wall of the body with the aligning openings of said pair of members in aligning relation with the opening provided by the hoop of said body, and a locking member slidably carried by the top edge of said front wall of the body including a locking shank adapted to extend into the aligning openings for locking the closure on the body.
8. In combination a chest including a body portion and a closure, said body and closure including intermeshing portions having transverse openings therein, a locking member movably carried to extend into said openings and lock the closure shut on said body, and a lock mechanism adapted to lock the locking member in locked position.
9. A chest comprising a body including a front wall, a bottom, a back wall, and end walls, said front wall at the top edge thereof having a recess inwardly thereof, a locking member slideable in said recess, a member carried by the body extending into the recess and providing an opening aligning with the recess, a closure hingedly carried by the back wall of said body, a member carried by said closure at the free end thereof providing a projecting portion having a transverse opening therein, said projecting portion when the closure is shut being adapted to extend into the recess of the front wall of said body with the opening of said projection in aligning relation with said recess and the opening of the member of said body whereby the sliding lock member upon movement may enter said aligning openings and lock the closure on said body.
10. A chest comprising a body including a front wall, a bottom, a back wall, and end walls, said front wall at the top edge thereof having a recess inwardly thereof, a locking member slideable in said recess, a member carried by the body extending into the recess and providing an opening aligning with the recess, a closure hingedly carried by the back wall of said body, a member carried by said closure at the free end thereof providing a projecting portion having a transverse opening therein, said projecting portion when the closure is shut be-

ing adapted to extend into the recess of the front wall of said body with the opening of said projection in aligning relation with said recess and the opening of the member 5 of said body whereby the sliding lock member may enter the openings and lock the closure on said body, and a lock member including a bolt adapted to engage the sliding lock member to hold the same locked.

10 11. In a chest construction the combination of a body including a bottom, front and rear walls, and end walls, a closure hingedly connected to the rear wall of said body, said front wall of the body at the top edge thereof 15 of providing inwardly extending recesses, sliding locking members in said recesses adapted to move longitudinally of the chest within the area of the front wall of said body, a member carried by the front wall 20 of the chest adjacent each of said recesses extending upwardly into each of said recesses and providing a transverse opening aligning with the recesses, spaced members carried by the closure including projecting 25 ends so that a pair of each of said ends are adapted to extend into each of said recesses of the front wall when the closure is shut, said projecting ends providing transverse 30 openings therein adapted to align with the opening in said member of the front wall to receive the sliding locking members therein whereby to lock the closure on said body.

12. In a chest construction the combination of a body including a bottom, front and 35 rear walls, and end walls, a closure hingedly connected to the rear wall of said body, said front wall of the body at the top edge thereof of providing inwardly extending recesses, sliding locking members in said recesses 40 adapted to move longitudinally of the chest within the area of the front wall of said body, a member carried by the front wall of the chest adjacent each of said recesses extending upwardly into each of said recesses 45 and providing a transverse opening aligning with the recesses, spaced members carried by the closure including projecting ends so that a pair of said ends are adapted to extend into each of said recesses of the 50 front wall when the closure is shut, said projecting ends providing transverse openings therein adapted to align with the opening in said member of the front wall to receive the sliding locking members therein whereby to lock the closure on said body, and key operated lock members for locking the sliding lock members in locked position.

55 13. A chest comprising a body including front and rear walls, a bottom, and end 60 walls, diagonal brace means interiorly of each of said walls secured thereto and in

crossed relation for each of said walls, corner clips at the lower corners of said body, a closure hingedly connected to said rear wall of the body including a top wall and front 65 and rear and end flanges, corner clips for said closure, diagonal brace means crossed at the inside surface of said top wall, transverse hoops enveloping the body and closure and at the free end of the closure providing 70 interengaging portions with transverse openings therein, and a locking member slidably on said body adapted to enter the transverse openings to lock the closure on the member. 75

14. A chest comprising a body including front and rear walls, a bottom, and end walls, diagonal brace means interiorly of each of said walls secured thereto and in crossed relation for each of said walls, corner clips at the lower corners of said body, a closure hingedly connected to said rear wall of the body including a top wall and front 80 and rear and end flanges, corner clips for said closure, diagonal brace means 85 crossed at the inside surface of said top wall, transverse hoops enveloping the body and closure and at the free end of the closure providing interengaging portions with transverse openings therein, a locking member 90 slidably on said body adapted to enter the transverse openings to lock the closure on the member, and key operated lock mechanism including a bolt adapted to extend into engagement with the locking member to 95 hold the same locked.

15. A chest of the class described comprising a body including a bottom, front and rear walls and end walls, transverse hoops exteriorly enveloping the body secured to the front and rear and bottom walls, and end 100 brace means secured to said transverse hoops and extending about the end and front and rear walls, diagonal brace means interiorly of said walls, and means securing said interior diagonal brace means and walls with the transverse hoops and end brace means. 105

16. A chest of the class described comprising a body including a bottom, front and rear walls and end walls, transverse hoops exteriorly enveloping the body secured to the front and rear and bottom walls, end brace means secured to said transverse hoops and extending about the end and front and rear walls, diagonal brace means interiorly of said walls, corner members secured to said body and the ends of said diagonal cross braces, and means securing the diagonal brace means and walls with the exterior hoops and end brace means. 110 115

EARCLE DICKSON.
